DESIGN FOR A COMBINED PLACE CARD HOLDER, NUT DISH, AND ASHTRAY

Edgar Mott Bottome, Moundsville, W. Va., assignor to Fostoria Glass Company, Moundsville,
W. Va., a corporation of West Virginia

Application November 17, 1936, Serial No. 65,980

Term of patent 3½ years

To all whom it may concern:

Be it known that I, Edgar Mott Bottome, a citizen of the United States of America and a resident of Moundsville, county of Marshall, and State of West Virginia, have invented a new, original, and ornamental Design for a Combined Place Card Holder, Nut Dish, and Ashtray, of which the following is a specification, reference being had to the accompanying drawing, in which—

Figure 1 is a front elevation of a combined place card holder, nut dish, and ashtray, showing my new design;

I claim—

The ornamental design for a combined place card holder, nut dish, and ashtray, substantially as shown.

EDGAR MOTT BOTTOME.
